UNITED STATES PATENT OFFICE.

CARL G. CONFER, OF SUMMITHILL, PENNSYLVANIA.

TOY VEHICLE.

1,358,188.

Specification of Letters Patent. Patented Nov. 9, 1920.

Application filed February 5, 1920. Serial No. 356,475.

To all whom it may concern:

Be it known that I, CARL G. CONFER, a citizen of the United States, residing at 5 Summithill, in the county of Carbon and State of Pennsylvania, have invented certain new and useful Improvements in Toy Vehicles, of which the following is a specification.

One object of my invention is to provide 10 a toy vehicle in the form of a flying machine which will be so constructed that a child can propel the same while sitting therein.

Another object is to so construct my invention that a child can easily get into or 15 out of the seat and at the same time the seat will be normally covered by an imitation plane or wing.

A further object is to provide steering 20 means which can be easily operated by a child while on the seat.

A still further object is to make the vehicle of a strong and durable construction 25 which will provide healthful amusement for children.

These objects, and other advantageous 30 ends which will be described hereinafter, I attain in the following manner. Reference being had to the accompanying drawings in which—

Figure 1 is a perspective view of a toy 35 vehicle constructed in accordance with my invention.

Fig. 2 is a sectional elevation of my improved toy vehicle taken centrally through 40 the length thereof.

Fig. 3 is an inverted plan view of Fig. 2, and

Fig. 4 is a transverse sectional elevation 45 taken on the line 4—4 of Fig. 2 showing, in full lines, a hinged section of an upper plane or wing in its open position.

Referring to the drawings, 5 represents a hollow body portion which has an opening 6 between its front and rear ends. A seat 45 7 is slid within said body portion below the opening 6. The bottom 8 of the body portion directly in front of the seat 7 is discontinued to provide an opening 9 which is located directly over a crank axle 10. This crank axle is journaled in two bearings 11 which depend from the body portion 5 and has two integral cranks 12 and 13 bent therein; said cranks being preferably set at 180° to each other. Ground-engaging 50 driving wheels 14 are mounted on the axle 10 at positions outside of the bearings 11.

One of the wheels 14 is secured to said axle 10 while the other runs freely to assist in the steering of the vehicle.

The body portion 5 of the seat 7 tapers 60 rearwardly and has a yoked bearing 15 pivotally secured thereto. A short axle 16 is journaled in the bearing 15 and has end portions 17 which project beyond the sides 65 of the bearing 15, as clearly shown in Fig. 3.

Flexible cables 18 and 19 are respectively connected to the opposite ends 17 of the axle 16 and these cables cross under the body portion at 20 and then pass through eyelets 21 on the bottom edges of the sides 70 of the body portion. The opposite ends of the cables are secured to a cross arm 21 on a steering post 22; said steering post extending at a slant through the bottom 8 and being provided with a hand wheel 23 which is 75 positioned above the seat 7. A ground-engaging steering wheel 24 is rotatably mounted on the short axle 16 within the yoked bearing 15 and it will thus be noted that by turning the hand wheel 23 that the steering wheel 24 will be turned to steer the vehicle 80 in the direction in which the hand wheel is turned.

Boards 25 extend laterally from the sides 85 of the body portion and are supported upon rails 26, as clearly shown in Fig. 4. Posts 27 extend upwardly from the boards 25 and at their tops support other boards 28 which are substantially parallel with the boards 25 and are spaced apart. A board 29 has one end hinged at 30 to an edge of one of the boards 28 and said board 29 is adapted to bridge the space between the boards 28 so that the boards 28 and 29 form an imitation upper plane of a flying machine. The 90 boards 25 present the appearance of the lower plane of a flying machine. The board 29, which will be considered as a section of the upper plane or wing, is directly above the opening 9 and seat 7 and normally is positioned above the head of a child sitting upon the seat 7. The section 29 can be raised as shown in full lines in Fig. 4 to permit the child to get into or out of the seat. 95

The rear of the body portion has a tail 100 vane 31 secured thereto; said tail vane having an extension 32 which can be made of sheet metal and partly wrapped around the body portion and secured to the bottom edges of the bottom portion as shown at 33 110 in Fig. 3. Also I preferably mount an imitation propeller 34 on the front end of the

body portion; said propeller being capable of being turned on a stud bolt 35 as a pivot; the stud bolt being secured in the extreme front end of the body portion as clearly shown in Figs. 1 and 2.

By the above construction it will be noted that a child sitting upon the seat 7 can propel the vehicle by moving the feet directly in engagement with the cranks 12 and 13 and the vehicle can be readily steered by turning the hand wheel 23.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A toy vehicle of the character described including a hollow body portion; ground-engaging wheels supporting said body portion, said body portion having an opening in its top and a seat located below said opening; and an imitation plane above the level 25 of said seat, said plane having a hinged cen-

tral section located directly over the seat in the body portion and capable of being swung open to provide a space to permit a child to get into and out of the opening in the body portion; substantially as described.

35

2. A toy vehicle of the character described including a body portion having sides and front and rear parts providing an opening; a seat located within said opening; an imitation plane above the level of said seat, 40 said plane having a hinged central section located directly over the seat in the body portion and capable of being swung open to provide a space to permit a child to get into and out of the opening in the body portion; other portions representing lower imitation plane sections projecting laterally from and secured to said body portion below the opposite end portions of said top plane; and posts connecting said end portions of 45 the top plane and the lower plane sections; substantially as described.

45

In testimony whereof I have signed my name to this specification in the presence of two subscribing witnesses.

CARL G. CONFER.
